JOHN W. BROSZKI, HENRY L. HARVEY, AND CLIFTON S. RINER, OF RICHMOND,
VIRGINIA.

PISTON FOR INTERNAL-COMBUSTION ENGINES.

Application filed November 23, 1925. Serial No. 70,925.

The object of this invention is to provide a piston with a cushion band for mounting the usual piston ring.

A further object is to eliminate vibration or lateral play of the piston, and avoid scoring the cylinder, by making special provision for taking up wear and providing for the clearance required in order to permit the piston to operate correctly.

10 A further object is to provide a hollow piston with chambered portions extending inwardly, the side walls having annular shoulders, and the side and end walls being formed with the body of the piston and projecting inwardly with reference thereto.

With the foregoing and other objects in view, the invention consists in the novel construction and arrangement of elements described, illustrated and claimed, it being 20 understood that modifications may be made within the scope of the claim, without departing from the spirit of the invention.

In the drawings forming part of this application,

25 Figure 1 shows the piston in vertical section and elevation.

Figure 2 is a transverse section on line 2—2 of Figure 1.

30 Figure 3 is a plan view of the cushion band, detached.

The piston 10 is formed as a hollow body and includes the inwardly and radially extending portion 11 providing chambers 12 for receiving radially extended springs.

35 The springs are shown as being coiled resilient elements 13, the inner ends abutting the end walls of the chambered portions.

The side walls of the piston are provided with annular channels 14 adapted to receive the cushion bands 15, and within bands 15 40 annular channels 16 are formed for the reception of the piston rings 17. An upper piston ring 18 is also illustrated. The annular channels may be rectangular in cross section, and the ends of the band 15 may 45 overlap in the manner shown in 15' in Figure 3.

The coiled springs 13 bear against the inner portions of bands 16, and the projections 19 serve to retain the outer ends of 50 the springs in correct position.

The operation of the device will be clear, and the advantages have been quite fully brought out.

What is claimed is:

55 The combination with a hollow piston formed with inwardly extending radial bores, of springs within the bores, an annular band having radial projections thereon, with rounded ends, for centering the 60 springs, the piston having an annular channel receiving the band, the diameter of the bores being less than the width of the band, providing a continuous bearing for the edges 65 of the band and said band having an annular channel, and a piston ring mounted within the channel of the cushion band.

In testimony whereof we affix our signatures.

JOHN W. BROSZKI.
HENRY L. HARVEY.
CLIFTON S. RINER.
